UNITED STATES PATENT OFFICE

OSTRANDER J. PARKS, OF RIVER FOREST, ILLINOIS, ASSIGNEE TO GENERAL AMERICAN
TANK CAR CORPORATION, OF CHICAGO, ILLINOIS, A CORPORATION OF WEST
VIRGINIA

VALVE MECHANISM

Application filed December 19, 1927. Serial No. 241,084.

My invention relates to valve mechanisms of the type comprising a valve proper for co-operation with a valve-seat, a stem, and means operating upon the rotating of the stem to actuate the valve proper; my invention having been devised for embodiment more particularly in valve mechanisms in which the valves proper move in a substantially vertical direction relative to valve-seats beneath them, but not to the exclusion of mechanisms in which the valves are disposed to operate in other directions and the valve-seats are otherwise disposed.

One of my objects is to provide a valve mechanism of the type referred to whereby the valve proper in the manipulating of the stem is caused to rotate against the valve-seat with which it cooperates to effect grinding of the valve proper against the seat, but not during the time that the valve proper is pressed against the seat by the final valve-closing pressure exerted by the stem, it being preferred that the valve rotating grinding operation be effected not only in the movement of the valve to closed position with discontinuation of the valve-rotating operation upon the final act of forcing the valve proper to the seat, but also in the movement of the valve proper to open position following the releasing of the pressure holding the valve proper against the seat.

Another object is to provide a valve construction in which provision is made for so rotating the valve proper against the seat that these parts will be ground substantially uniformly throughout their opposing surfaces.

Another object is to provide a valve mechanism of the type referred to the end that if desired, the valve proper may be freely rotated on the seat for the purpose of grinding in the valve, and without disassembling the parts; and other objects as will be manifest from the following description.

Referring to the accompanying drawings wherein I have illustrated my invention as embodied in a valve mechanism controlling the discharge outlet in the bottom of the tank car:

Figure 1 is a broken view in sectional ele-

vation of the outlet-equipped bottom portion of a tank car with valve mechanism associated therewith for controlling said outlet and embodying my invention. Figure 2 is an enlarged section taken at the line 2—2 on Fig. 1 and viewed in the direction of the arrows. Figure 3 is an enlarged section taken at the line 3—3 on Fig. 1 and viewed in the direction of the arrows. Figure 4 is a broken sectional view taken at the line 4 on Fig. 3 and viewed in the direction of the arrow. Figure 5 is a view in side elevation of the valve proper of the mechanism. Figure 6 is a plan view of the valve proper of Fig. 5. Figure 7 is a view in elevation of the lower end of the valve actuating stem. Figure 8 is a similar view of the part of the stem shown in Fig. 7 but viewed from a position normal thereto. Figure 9 is a section taken at the line 9—9 on Fig. 7 and viewed in the direction of the arrows; and Figure 10, a section taken at the line 10—10 on Fig. 7 and viewed in the direction of the arrows.

In the particular construction illustrated, 11 represents the bottom sheet of a tank car containing an outlet-opening 12. Fitting flatwise at its upper surface against the underside of the bottom sheet 11 to extend across the opening 12, is a tank outlet member 13 shown as in the form of an outlet-leg riveted to the bottom sheet 11 as represented at 14, the upper end of this outlet-leg being provided with an annular seat 15 shown as of mitre form and with which cooperates the valve proper 16 of valve mechanism provided for the purpose of controlling the flow of material from the tank through the outlet of the latter.

The valve proper 16 is shown as provided with a peripheral mitred seating surface 17 at which it is adapted to engage with the seat 15 and is formed with depending guide wings 18 which extend into the bore of the leg 13.

The upper end portion of the valve proper 16 contains an upwardly opening, transversely disposed, groove 19 the bottom surface of which is preferably rounded as represented at 20. The upper portion of the groove 19 is restricted as represented at 21 and provides the parallel shoulder surfaces 22.

Rising from, and rigidly secured to, the leg 13 within the confines of the opening 12, is a series of screw bolts 23, forming studs, four of these studs arranged in a rectangular formation comprising the series in the particular construction shown, though the number and arrangement thereof may be varied as desired, these studs screwing into upwardly-opening threaded sockets in the leg 13 and 10 represented at 24. The studs 23 serve as a support for a nut 25 shown as of spider form, this nut containing openings 26 at its marginal edge portion to receive the upper ends of the studs 23 provided with nuts 27 between which and shoulders 28 on the studs 23, the nut 25 is firmly clamped in position.

The spider nut 25 at its central threaded portion is vertically thickened as shown to form a hub portion 29 substantially in vertical alignment with the valve proper 16.

Screwing in the hub portion 29 is a threaded rod 30, forming a valve stem to the upper end of which the lower end of an operating rod 31 is connected. The rod 31 which would 25 extend at its hand-wheel-equipped portion 32 to a point accessible for rotation by the operator in accordance with well known practice, is shown as journaled in a bracket 33 secured to a side wall 34 of the tank, the lower 30 end of this rod being shown as formed with a downwardly-opening socket portion 35 into which the upper end of the threaded stem 30 extends and to which it is secured as for example by a cotter-pin 36 extending through 35 the socket portion 35 and the upper end of the stem 30.

The lower end portion of the valve stem 30 extends into the groove 19 in the valve proper 16, and is shown as comprising a head 40 37 with its undersurface of general spherical form as represented at 38, this head being of greater width than the width of the restricted portion 21 of the groove 19. The valve stem 30 is formed with a neck portion 45 39 between the head 37 and the body portion of the stem 30, this neck portion, which extends into the restricted portion 21 of the groove 19, being of greater length than the height of this restricted portion, as shown. The neck portion 39 comprises the flat sided 50 elongated portion 40 adjacent the head 37 and the cylindrical portion 41 of a diameter slightly less than the width of the restricted portion 21 of the groove 19, and of a length 55 slightly greater than the thickness of the walls of the portion 21.

Assuming that the valve is in open condition in which condition the valve proper 16 60 dependently hangs from the valve stem 30 by the engagement of the walls forming the restriction 21 of the groove 19, with the upper surface of the head 37 of the stem; the operator, to close the valve, rotates the stem 30 in clockwise direction in Fig. 3, the valve 65 proper 16 lowering with the stem until the

valve proper engages at its portion 17 with the valve seat 15. In this lowering operation as stated the elongated portion 40 of the neck of the valve stem extends into the restricted portion 21 of the groove 19 thereby forming an interlock between the valve proper 16 and the stem so that the valve proper 16 is rotating as it engages the seat 15, and it continues to rotate against this seat until the portion 40 of the stem, in the continued rotation of the latter, moves downwardly out of the restricted portion 21 of the groove which occurs in the particular construction shown immediately preceding the forcing of the valve proper 16 against the seat 15 for forming the desired tight closure which is effected, in the particular arrangement shown, by the forcing of the head 37 downwardly against the bottom wall of the groove 19, in the continued rotation of the valve stem 30, it being noted that by the time the valve stem 30 has moved downwardly to a position in which it starts to force the valve proper 16 against the seat 15, the cylindrical portion 41 of the valve stem 30 is the only portion of the latter which extends into the restricted portion 21 of the groove, which permits the stem to rotate without rotating the valve proper 16.

In the opening of the valve, by rotation of the stem in counterclockwise direction in Fig. 3, the stem 30 rotates independently of the valve proper 16 to a point where downward pressure by the stem on the valve, is released. By this time the elongated portion 40 of the stem will enter the restricted portion 21 of the groove forming an interlock therewith for rotating the valve proper 16 on the seat 15, under the weight of the valve proper 16, until the stem 30 has been rotated sufficiently far to lift the valve proper 16 from the seat 15 by engagement of the head 37 with the side walls of the restricted portion 21 of the groove, whereupon the valve proper 16 will move bodily upward with the stem 30.

It will be understood from the foregoing that a valve structure constructed in accordance with my invention provides for the automatic grinding in of the valve proper 115 and the seat cooperating therewith under relatively light pressure uniformly applied, as distinguished from the non-uniform pressure which is produced where the valve is caused to rotate against its seat during the 120 final seating of the valve.

Furthermore, by reason of the provision of the drive connection between the stem and the valve proper as shown and described the 125 final seating of the valve is not consecutively in the same position which is of great advantage as thereby wear of the valve and seat at one point of contact is avoided and instead the wear of the valve and seat is caused to be substantially uniform and consequently 130

there is a uniform distribution of wear which makes for the production of better joints.

Another advantage of my improved construction consists in the ease with which the valve proper may be ground in if desired, as for example by a prolonged rotation of the valve proper on its seat. By slightly backing off the stem to relieve the pressure of the latter against the valve proper 16 tending to force it to the seat the valve proper may be freely rotated on the seat 15 by hand or by any desired mechanical contrivance. The further backing off of the stem 30 to a position in which the elongated portion 40 of the stem extends into the restricted portion 21 of the groove, permits the valve proper 16 to be rotated on its seat merely by rotating the stem 30 as through the means of the rod 31 or a wrench, or other means for rotating the valve through the medium of the stem, applied to the latter after disconnecting the rod 31 therefrom.

It will also be noted that a valve structure constructed as shown and involving the studs 23 disposed in the arrangement as shown for supporting the nut 25 permits of the grinding in of the valve seat, even when a grinding compound is to be supplied to these parts, without requiring the disassembling of the parts of the valve.

While I have illustrated and described a particular construction embodying my invention, I do not wish to be understood as intending to limit it thereto as the same may be variously modified and altered without departing from the spirit of my invention.

What I claim as new, and desire to secure by Letters Patent, is:

1. In valve mechanism, the combination with a valve-seat-equipped member, a valve proper for cooperation with said seat, a stem having a head at its inner end for engagement with said valve proper, said head engaging the center of said valve proper, means operating, when said stem is rotated, to move said stem lengthwise, and means for actuating said valve proper by said stem constructed and arranged to rotate said valve proper against said seat during a portion only of the movement of said stem in a direction toward said seat and thereafter discontinue said rotation and force said valve proper to said seat.

2. In valve mechanism, the combination with a valve-seat-equipped member, a valve proper for cooperation with said seat, a stem, and means operating, when said stem is rotated, to move the latter lengthwise, said valve proper having a portion containing a non-circular opening therethrough and said stem having a portion which is adapted to be laterally inserted into said opening and to reside therein, said stem being so formed as to force said valve proper against said seat in the rotation of said stem in one direction

and said portion of said stem being of greater length than the thickness of said apertured portion of said valve proper and so formed that in the relative lengthwise movement of said valve proper and said stem to seat said valve proper, but only throughout a portion of such movement, said stem interlocks with said valve proper to rotate said valve proper on said seat and during the remainder of such movement said stem is free to rotate independently of said valve proper.

3. In valve mechanism, the combination with a valve-seat-equipped member, a valve proper for cooperation with said seat, a stem, and means operating, when said stem is rotated, to move the latter lengthwise, said valve proper having a portion containing a non-circular opening therethrough and said stem having a neck portion terminating in a head, said neck portion extending into said opening, and said head being adapted to exert pressure on said valve proper for forcing the latter to said seat, the portion of said neck adjacent said head being adapted to interlock with the apertured portion of said valve proper and the other portion of said neck being of a length greater than the thickness of the wall of said apertured portion of said valve proper and so formed as to permit said stem to rotate in said valve proper.

4. In valve-mechanism, the combination with a valve-seat-equipped member, a valve proper for cooperation with said seat, and arranged above, and seating downwardly against, said seat and pressing against the latter except when forced upwardly from said seat, a stem, and means operating, when said stem is rotated, to move the latter lengthwise, said valve proper having a portion containing a non-circular opening therethrough and said stem having a portion which extends laterally into said opening, said stem being so formed as to force said valve proper against said seat in the rotation of said stem in one direction and said portion of said stem being of greater length than the thickness of the portion of said valve proper containing said opening and so formed that in the relative lengthwise movement of said valve proper and said stem to seat said valve proper, but only throughout a portion of such movement, said stem interlocks with said valve proper to rotate said valve proper on said seat and during the remainder of such movement said stem is free to rotate independently of said valve proper.

5. In valve mechanism, the combination with a valve-seat-equipped member, a valve proper for cooperation with said seat, a stem having a head at its inner end for engagement with said valve proper, the surface of said head at which it engages said valve proper being of spherical form to provide a center contact, means operating, when said stem is rotated, to move said stem lengthwise,

and means for actuating said valve proper by said stem constructed and arranged to rotate said valve proper against said seat during a portion only of the movement of said stem in a direction toward said seat and thereafter discontinue said rotation and force said valve proper to said seat.

6. In valve mechanism, the combination with a valve-seat-equipped member, a valve proper for cooperation with said seat, a stem, and means operating, when said stem is rotated, to move the latter lengthwise, said valve proper having a portion containing a non-circular opening therethrough and said stem having a portion which extends into said opening, said stem having a head which engages said valve proper and forces the latter against said seat in the rotation of said stem in one direction and said portion of said stem being of greater length than the thickness of said apertured portion of said valve proper and so formed that in the relative lengthwise movement of said valve proper and said stem to seat said valve proper, but only throughout a portion of such movement, said stem interlocks with said valve proper to rotate said valve proper on said seat and during the remainder of such movement said stem is free to rotate independently of said valve proper, said head being below that portion thereof containing said opening, and operating to lift said valve proper in the raising of said stem.

7. In valve mechanism, the combination with a valve-seat-equipped member, a one-piece valve proper for cooperation with said seat, a stem, and means operating, when said stem is rotated, to move the latter lengthwise, said valve proper having a transversely disposed slot extending crosswise thereof and opening at one end through a side of said valve proper, the upper portion of said slot being constricted and said stem having a portion which extends into said slot, said stem being so formed as to force said valve proper against said seat in the rotation of said stem in one direction and said portion of said stem being of greater length than the thickness of said slotted portion of said valve proper and so formed that in the relative lengthwise movement of said valve proper and said stem to seat said valve proper, but only throughout a portion of such movement, said stem interlocks with said valve proper at said constricted portion of said slot to rotate said valve proper on said seat, and during the remainder of such movement said stem becomes disengaged from interlocking relationship with said slot and becomes free to rotate independently of said valve proper, said stem having a head extending into the portion of said slot of greater width and being wider than the restricted portion of said slot.

OSTRANDER J. PARKS.
